[57] **CLAIM**

The ornamental design for a motorcycle protective shoe cover, as shown and described.

DESCRIPTION

FIG. 1 is a top, front and left side perspective view of a motorcycle protective shoe cover, showing our new design; FIG. 2 is a top, front and right side perspective view thereof; and,

FIG. 3 is a bottom view thereof.

The broken line showing of the shoe and boot in the Figures is for illustrative purposes only and forms no part of the claimed design.

The parallel lines in FIG. 3 represent treads.
